HURXTHAL FIELD FREASE, OF CANTON, OHIO

TRUSSSED STRUCTURE

Application filed December 12, 1925. Serial No. 74,988.

The invention relates to trussed structures having spaced chord members and connecting web members joined together; and more particularly to trussed structures for use as pendulously supported floor joists.

Trussed floor joists are usually supported at their end, and it is desirable that these ends have centers of gravity adapted for stable equilibrium and be of such construction as to resist not only shear loads, but also any bending loads which any accidental or purposeful fixing of the joist ends may induce.

Moreover, a trussed floor joist may be supported at suitably constructed ends, but may fail as the result of secondary stresses set up in the members under a load less than that which would cause failure by the primary direct stresses set up by frame structure or truss action in the joist.

Such a secondary failure may be indicated by buckling of the upper compression chord members of a trussed floor joist under usual conditions of loading.

Buckling may, of course, be the result of the primary direct compression stresses set up in the upper chord members by the truss action of the joist when loaded.

Such buckling may also be induced by the secondary bending stresses set up in the upper chord members of a trussed joist, since the upper chord members under ordinary loading conditions are themselves continuous beams, or a series of short beams supported at the junctions of the chord and web members of the joist.

The relative effect of these primary and secondary stresses is, of course, determined by the distance between the junctions of the truss chord and web members, and by the nature of the loading.

Ordinary floor joists are usually designed for loads uniformly distributed over the span, in which case the maximum bending stresses are set up in the central portions of the truss chord members.

Other types of loading may set up maximum stresses elsewhere in the chord members whose location and magnitude may be

determined by the methods of the science of structures.

In cases where it is possible to predict where the maximum bending stresses will be set up, it is desirable to reinforce the truss members subject to these maximum stresses.

On the other hand, where it is desired to attain a trussed structure having a minimum weight for a given type of loading, maximum stress reinforcing should be eliminated from truss members not subject to maximum stresses.

The objects of the present invention are to provide a trussed structure more particularly for use as a pendulously supported floor joist and which shall have ends adapted to resist shear and bending loads as aforesaid, and which may be provided with reinforcing to resist primary and/or secondary stresses, and reinforcing for the truss members subject to maximum stresses.

A further object of the invention is to provide such a trussed structure provided with suitable ends which have centers of gravity adapted for stable equilibrium.

A further object of the invention is to provide a trussed structure which may have a minimum weight for a desired loading, and which may for production economy be made of bar parts all having the same cross section.

These objects are attained by the use of spaced shear and bending reinforcing plates, a plurality of spaced chord bars, and a web secured between the spaced plates and to the chord bars, the web being preferably made from a continuous bar or strip of material, and including a truss element, and/or a zig-zag element, and terminals spaced between the plates and secured thereto and to the chord bars and forming box beam ends.

Several embodiments of the invention are illustrated in the accompanying drawings forming part hereof, in which—

Figure 1 is a side elevation of one form of the improved trussed structure for use as a pendulously supported floor joist, and which includes a web preferably made from a continuous bar or strip of material, the web including a truss element having spaced chord

and web members connected to each other at preferably abutting apexes for a portion of the joist span, a zig-zag element having connected web members for other portions of the span, and terminals for the joist ends including upper and lower chord members connected to each other by members angular thereto, and to the other members of the web, the web being secured between spaced shear and bending reinforcing plates, and to a plurality of spaced chord bars.

Fig. 2, side elevations of disassembled bar and plate members for the joist of Fig. 1;

Fig. 3, a vertical cross section of the same as on line 3—3, Fig. 1;

Fig. 4, another vertical cross section of the same as on line 4—4, Fig. 1;

Fig. 5, a vertical cross section of the joist end as on line 5—5, Fig. 1;

20 Fig. 6, a side elevation of a modified form of the invention for use as a pendulously supported floor joist, similar to that illustrated in Fig. 1, but differing therefrom in that the span portion of the web consists of zig-zag connected web members;

Fig. 7, side elevations of disassembled plate and bar members for the joist of Fig. 6;

Fig. 8, a vertical cross section of the same as on line 8—8, Fig. 6;

30 Fig. 9, a vertical cross section of the end of the same as on line 9—9, Fig. 6;

Fig. 10, a side elevation of another modification of the invention for use as a pendulously supported floor joist, in which the spaced shear and bending reinforcing plates do not extend across the entire joist span and in which the span portion of the web consists of a truss element including spaced chord and web members connected to each other at junction angles;

Fig. 11, side elevations of the bar members for the joist of Fig. 10;

Fig. 12, an enlarged, fragmentary side elevation of the end of the joist of Fig. 10, a portion of one shear and bending reinforcing plate being broken away to illustrate the vertical connection between the upper and lower chord portions of the web terminal; and

50 Fig. 13, a vertical cross section of the same as on line 13—13, Fig. 12.

Similar numerals refer to similar parts throughout the drawings.

The improved trussed structure indicated generally at 1 in Figures 1, 3, 4 and 5, and 55 whose disassembled parts are illustrated in Fig. 2, includes spaced plates 2, spaced upper chord bars 3, spaced lower chord bars 4, and a web indicated generally at 5 secured between the spaced plates and to the chord bars as by arc welding 6, the web being preferably made from a continuous bar or strip of material, and including a truss element indicated generally at 7, zig-zag elements indicated generally at 8, and terminals indicated 65 generally at 9.

The truss element 7 of the web 5 includes spaced chord members 10 and connecting web members 11, there being preferably abutting apexes 12 between the chord and web members.

70 The zig-zag elements 8 of the web 5 include connected web members 11', there being alternate apexes 12' between the web members.

The terminals 9 of the web 5 include upper chord members 13, and lower chord members 14 connected to each other by members angular thereto including vertical end members 15 and diagonal members 16 and 17, the chord members 13 and 14 being preferably spaced parallel with each other as shown, and diagonals 17 preferably terminating in chord extensions 18 parallel with members 13 and 14.

80 The lower chord bars 4 include central portions 4^a provided near their ends with upwardly extending diagonal portions 19 connecting with terminals 20, said terminals being preferably parallel with the central portions 4^a.

The spaced plates 2 may be provided with bent up angle legs 2^a at their ends.

90 The structure 1 may thus be assembled from the parts illustrated in Fig. 2 by interposing a web 5 between a pair of spaced plates 2 arranged along the upper longitudinal edge of the web and securing the plates to the web and to the spaced upper and lower chord bars 3 and 4 as by arc welding 6 to form the completed structure 1.

95 Spaced terminal chord bars 13 and 14 and their connecting end bar 15 are secured to the outer boundaries of the plates 2, thus forming box beam ends for the joist which are further strengthened by the terminals of the chord bars 3 and 4 secured thereto as best illustrated by the cross-section view of Fig. 5.

100 The box ends thus formed have centers of gravity more adapted for stable equilibrium against lateral tipping than are other types of ends for bar joists and which may have end plates not spaced nor secured to an interposed web bar terminal, or which may consist merely of a T-bar welded to the terminals of the chord bars.

105 The spaced plates may extend the entire length of the joist as illustrated in Figure 1, in which case a reinforcing is provided for resisting either primary or direct stresses in the upper chord members of the structure. In fact if the plates 2 extending the entire length of the joist be of sufficiently heavy gauge material upper chord bars 3 might be entirely eliminated or utilized only to provide lateral stiffness for the joists.

110 By providing the centrally located truss element 7 in the web, that portion of the trussed structure between the terminals of the truss element 7 has a greater moment of inertia than those portions of the trussed structure between the terminals of the zig-zag elements 8, thus providing an efficient struc-

ture for use under a uniformly distributed load or a load concentrated near the center of the span, under which conditions the maximum imposed bending moment occurs near the center of the span, decreasing to zero at the supports if the joist be freely supported at its ends.

Consequently, for resisting such a type of loading the required moment of inertia in the central portions of the joist is greater than the required moment of inertia between the central portions and the ends; so that a construction which enables the fabrication of a joist having a varying moment of inertia provides a joist having a minimum weight for the required strength.

The construction of the present invention enables the construction of a bar joist having a varying moment of inertia and ends adapted to resist shear and bending loads as heretofore described, and which may be made of bar parts all having the same cross sectional area, which is very desirable from the standpoint of stores and production economy.

The cross section of Fig. 4 as compared with the cross section of Fig. 3 illustrates that a greater moment of inertia is attained in the joist at 4-4 than at 3-3 both of which sections are between web and chord apexes or panel points, since the chord area of the cross section at 4-4 is made up of three bar sections here illustrated as all being equal in area, while the cross sections at 3-3 is made up of only two bar sections here illustrated as being equal in area, it being assumed that for the purposes of this particular comparison the gauge of the plates 2 is sufficiently light not to materially affect the resisting moment of the joist.

The modified embodiment of the invention indicated generally at 2-1 illustrated in Figs. 6, 8 and 9, and whose disassembled parts are illustrated in Fig. 7, includes spaced plates 2-2, spaced upper chord bars 2-3, spaced lower chord bars 2-4, and a web indicated generally at 2-5 secured between the spaced plates and to the chord bars as by arc welding 2-6, the web being preferably made from a continuous bar or strip of material, and including a zig-zag element indicated generally at 2-8, and terminals indicated generally at 2-9.

The zig-zag element 2-7 of the web 2-5 includes connected web members 2-11', there being alternate apexes 2-12' between the web members.

The terminals 2-9 of the web 2-5 include upper chord members 2-13 and lower chord members 2-14 connected to each other by members angular thereto including vertical end members 2-15 and diagonal members 2-16 and 2-17, the chord members 2-13 and 2-14 being preferably spaced parallel with each other as shown, and diagonals 2-17 preferably terminating in a chord extension

2-18 parallel with members 2-13 and 2-14.

The lower chord bars 2-4 include central portions 2-4^a provided near their ends with upwardly extending diagonal portions 2-19 connecting with terminals 2-20, said terminals being preferably parallel with the central portions 2-4^a.

The spaced plates 2-2 may be provided with bent up angle legs 2-2^a at their ends.

Joist 2-1 differs from joist 1 in that a substantially constant moment of inertia is provided across the entire span by the elimination of the truss element 7 having chord portions 10.

For providing a modified form of joist having a substantially constant moment of inertia across its entire span somewhat greater than the moment of inertia attained by the construction illustrated in Fig. 6, and just described, a further modification of the invention may be employed which is illustrated in Figs. 10, 12 and 13, and whose disassembled parts are illustrated in Fig. 11.

This modified trussed structure indicated generally at 3-1 includes spaced plates 3-2, spaced upper chord bars 3-3, spaced lower chord bars 3-4, and a web indicated generally at 3-5 secured between the spaced plates and to the chord bars as by arc welding 3-6, the web being preferably made from a continuous bar or strip of material, and including a truss element indicated generally at 3-7 and terminals indicated generally at 3-9.

The truss element of the web 3-5 includes spaced chord members 3-10 and connecting web members 3-11, there being preferably abutting apexes 3-12 between the chord and web members.

The terminals of the web include upper chord members 3-13 and lower chord members 3-14 connected to each other by members angular thereto including vertical end members 3-15 and diagonal members 3-16 and 3-17, the chord members 3-13 and 3-14 being preferably spaced parallel with each other as shown, and the chord members 3-13 preferably abutting the terminal chord members 3-10 of the truss element 3-7.

The lower chord bars 3-4 include central portions 3-4^a provided near their ends with upwardly extending diagonal portions 3-19 connecting with terminals 3-20, said terminals being preferably parallel with the central portions 3-4^a.

The spaced plates 3-2 may be provided with bent up angle legs 3-2^a at their ends and may extend from their ends any desired distance towards the center of the span.

Joist 3-1 differs from the preceding embodiments of the invention in that the plates 3-2 do not extend across the entire length of the joist, and in that the web is provided with a truss element having chord portions across a greater portion of the span for pro-

viding a joist having a substantially constant moment of inertia somewhat greater than the substantially constant moment of inertia of the joist heretofore described and illustrated in Fig. 6.

5 I claim:

1. An end for a pendulously supported bar joist and the like including spaced plates, and the terminal of a continuous web bar interposed between the plates and secured thereto and the terminal including spaced upper and lower chord members.
- 10 2. An end for a pendulously supported bar joist and the like including spaced plates, the terminal of a continuous web bar interposed between the plates and secured thereto and the terminal including spaced upper and lower chord members, and chord bar terminals secured to the plates.
- 15 3. An end for a pendulously supported bar joist and the like including spaced plates, and the terminal of a continuous web bar interposed between the plates and secured thereto, the terminal including spaced chord members connected with each other endwise by a member angular to the chord members.
- 20 4. An end for a pendulously supported bar joist and the like including spaced plates, and the terminal of a continuous web bar interposed between the plates and secured thereto, the terminal including spaced chord members connected to the outer boundaries of the plates.
- 25 5. A structure for a pendulously supported bar joist and the like including spaced plates, a continuous web bar interposed between the plates and secured thereto, and chord bars secured to the web bar, the web bar including a bar terminal interposed between the plates and connected to the upper, end, and lower outer boundaries of the plates.
- 30 6. A structure for a pendulously supported bar joist and the like including spaced plates, a continuous web bar interposed between the plates and secured thereto, and chord bars secured to the web bar, the web bar including a bar terminal interposed between the plates and connected thereto, a zig-zag element including connected web members and alternate apexes between the web members, and a truss element including spaced chord members and connecting web members and apexes between the chord and web members.
- 35 7. A structure for a pendulously supported bar joist and the like including a plurality of spaced chord bars and a web secured thereto, the web including a zig-zag element including connected web members and alternate apexes between the web members, and a truss element including spaced chord members and connecting web members and apexes between the chord and web members.
- 40 8. A structure for a pendulously supported bar joist and the like including a plurality of spaced chord bars and a web secured there-

to, the web including a bar terminal interposed between the chord bars and secured thereto, a zig-zag element including connected web members and alternate apexes between the web members, and a truss element including spaced chord members and connecting web members and apexes between the chord and web members.

9 9. A web for a structure for a pendulously supported bar joist and the like including a zig-zag element including connected web members and alternate apexes between the web members, and a truss element including spaced chord members and connecting web members and apexes between the chord and web members, all the elements being formed in a single continuous bar.

10 10. A web for a structure for a pendulously supported bar joist and the like including a terminal including spaced chord members connected to each other by a member angular to the chord members, a zig-zag element including connected web members and alternate apexes between the web members, and a truss element including spaced chord members and connecting web members and apexes between the chord and web members, the terminal and the elements being formed in a single continuous bar.

11 11. A bar joist and the like having a central spanning of varying moment of inertia, and including upper and lower parallel chord bars each having a substantially uniform cross section and a continuous web bar of substantially uniform cross section.

In testimony that I claim the above, I have hereunto subscribed my name.
